UNITED STATES PATENT OFFICE

148,478

DESIGN FOR A COMBINED VANITY CASE AND LIPSTICK HOLDER

Ladislas Medgyes, New York, N. Y., assignor to Helena Rubinstein, Inc., New York, N. Y., a corporation of New York

Application July 11, 1946, Serial No. 131,481

Term of patent 7 years

(Cl. D86—10)

To all whom it may concern:

Be it known that I, Ladislas Medgyes, a citizen of Hungary and residing in the city, county, and State of New York, have invented a new, original, and ornamental Design for a Combined Vanity Case and Lipstick Holder, of which the following is a specification, reference being had to the accompanying drawings, forming part thereof.

Fig. 1 is a plan view of a combined vanity case and lipstick holder, showing my new design.

Fig. 2 is a rear elevational view of the same.

Fig. 3 is a side elevational view of the same.

I claim:

The ornamental design for a combined vanity case and lipstick holder, as shown.

LADISLAS MEDGYES.
